UNITED STATES PATENT OFFICE.

GLENN MORE, OF JAMESTOWN, NEW YORK, ASSIGNOR TO BLACKSTONE MANUFACTURING COMPANY, OF JAMESTOWN, NEW YORK, A CORPORATION OF NEW YORK.

REMOVABLE WRINGER MECHANISM.

1,328,754.

Specification of Letters Patent. Patented Jan. 20, 1920.

Application filed March 17, 1919. Serial No. 283,023.

To all whom it may concern:

Be it known that I, GLENN MORE, a citizen of the United States, and a resident of Jamestown, in the county of Chautauqua and State of New York, have invented certain new and useful Improvements in Removable Wringer Mechanisms; and I do hereby declare that the following is a full, clear, and exact description thereof, reference being had to the accompanying drawings, and to the letters of reference marked thereon, which form a part of this specification.

This invention relates to improvements in power driven washing machines.

One of the objects of the invention is to provide a novel and convenient arrangement whereby a wringer may be mounted upon a washing machine in such manner as to permit of its being swung in a horizontal plane into different positions for use, including a novel arrangement which will also permit of the bodily removal or detachment of the wringer from the machine, so that it may be more conveniently packed when the machine is crated for shipment.

Another object of the invention is to provide novel and improved mechanism for driving the wringer from a horizontal drive shaft, and co-operating mechanism whereby the direction of rotation of the wringer rolls may be reversed at will.

These and other objects of the invention will more fully appear as I proceed with my specification.

In the drawings:

Figure 1 is a side elevation of the washing machine complete, partly broken away to show some of the parts more fully.

Fig. 2 is a top plan view, the position of the wringer in two of its several positions being indicated in dotted lines.

Fig. 3 is a side elevation of one end of the machine, showing the wringer detached, but in juxtaposition.

Fig. 4 is a front elevation, partly in section, of the levers for locking the wringer in the desired position.

Fig. 5 is a side elevation, partially in section, of the housing for the reversing mechanism, at the end of the horizontal drive shaft, and the bracket to which the wringer is attached, in operative position on said housing.

Fig. 6 is a view taken at right angles to that of Fig. 5, showing the means for controlling the reversing mechanism in elevation.

Fig. 7 is a sectional view of a part of the device shown in Fig. 5, the same being taken on the horizontal plane indicated by the dotted line 7-7 of Fig. 5.

Fig. 8 is a horizontal plan view, enlarged, of the driving shaft, showing some of the associated parts in section.

Fig. 9 is a perspective view of the removable guard plates which protect and cover the reversing gearing.

In the drawings: A represents a washing machine tub which is preferably of generally circular contour, and is provided with a movable top or lid B. The top of the tub is provided with a relatively narrow stationary part *a*, or support, upon which the driving mechanism may be mounted, said mechanism including the horizontally disposed driving shaft S.

The lid B is provided with suitable means for supporting the operating shaft C, having its lower end projecting within the tub and provided with any suitable means for engaging the garments to be washed. Any suitable means may be employed to transmit motion from the driving shaft S to the operating shaft C, and I have illustrated one such means, reserving the right to cover the same in another application.

M indicates an electric motor from which power may be communicated by a belt *m* to a pulley wheel P, mounted upon a shaft 10. A small spur pinion 11 is mounted upon the shaft 10 and is adapted to mesh with a larger spur gear 12 mounted upon a shaft 13. On the hub of the gear 12 and on that side of the spur gear 12 opposite the pulley P, is a bevel pinion 14 adapted to mesh with a bevel pinion 15 mounted upon a horizontal drive shaft S.

A metal plate or casting H is mounted upon the support *a* of the tub, and provides suitable and appropriate bearings at 16, 17 and 18, for the horizontal drive shaft S, and also bearings at 19 for the stub shaft 13, and at 20 for the shaft 10. A suitable cover or guard 22 extends over and protects the spur gears 11 and 12, and beveled pinion 14. An appropriately shaped cover or guard 23 likewise protects and incases the beveled pinion

15. It will be noted that the bevel pinion 15 is splined at 24 to the operating shaft S, and that, consequently, power communicated from the motor M through the belt m, the 5 pulley P, spur gears 11 and 12, and beveled pinions 14 and 15, will cause a continuous rotary motion to be imparted to the driving shaft S.

The driving shaft S may be provided on 10 its end with a crank K, to the outer arm of which is mounted the usual wrist pin k (reference being had to Figs. 1 and 2), which pin has a bearing in one end of a pitman or link L. This link L is connected at its other 15 end to a stud or pin 25 extending outwardly from the arm 26 projecting from a bearing sleeve 27.

The lid B is provided with a casting D carrying suitable supporting bearings 21 for 20 a rock shaft 28. The arm 26 is secured to one side of said sleeve 27 and the arm 29 on the other side. The end of the rock arm 29 is provided with a yoke 30 by which its members may be pivotally attached to the 25 vertical operating shaft C by the bolt and nut 31.

It will be understood that as the operating shaft S is rotated continuously in one direction, the crank end of the link L will 30 be rotated by means of the crank K about the end of the shaft S, while the other end of the link L will be reciprocated to impart a rocking motion to the rocking arms 26, 29. Thus continuous rotary motion of the operating shaft S will be translated into alternating or reciprocating vertical motion of the operating shaft C.

The tub A is shown as resting upon the top surface of a suitable bench, preferably 40 made of a metal frame of side and end bars 32, 33, supported upon corner standards 34, and strengthened by angularly disposed truss bars 35 and by cross bars 36, the latter extending horizontally between the standards 34. Any other form of tub support 45 may, obviously, be substituted for the metal bench herein shown. No claim is made to the metal support just described, the same being made the subject of a separate application.

I have stated above that the crank K is mounted upon the horizontal drive shaft S. It is, however, loosely mounted thereon, so that the shaft S may rotate without rotating 55 the crank. Means for rotating the crank comprise a shifting clutch which I will now proceed to describe. Said clutch comprises two members 37, 38. The member 37 is integral with or secured to one face of the 60 crank K. The member 38 is splined to and has constant rotation with the shaft S, the familiar spline connection affording the usual longitudinal sliding movement of the member 38 upon the shaft S. The adjacent 65 faces of the clutch members 37 and 38 have

the usual interlocking lugs and shoulders. When the member 38 is thus moved into interlocking engagement with the member 37, the crank K becomes locked to the shaft S and partakes of its rotary movement. An 70 annular groove 39 is placed in the periphery of the clutch member 38. Projecting in this groove is an upturned fork or stud member 40, located upon the end of a bell crank lever 41, pivotally mounted at 42 to the 75 casting H, which lever 41 is operated by a convenient handle 43. When the handle 43 is depressed, the fork or stud member 40 will move the clutch member 38 by means of its feathered or splined connection with 80 the shaft S, to slide lengthwise of the shaft S until it is in interlocking engagement with the clutch member 37 or vice versa.

As a means of holding the lever 41 in the raised position indicated in Fig. 1, thus 85 throwing the washing machine operating mechanism proper out of operation, while permitting the shaft S to continue its rotary movement, I provide as a locking mechanism, a pawl locking member 44 arranged 90 to engage a suitable notch 45 in the casting H, the locking pawl 44 being held in the position shown by means of a spring 46 interposed between the handle 43 and the pawl operating handle 47. The handle 47 and 95 48 are pivotally mounted on the handle 43 as shown at 48. Thus, in the raised or disengaged position of the parts just described, as illustrated in Fig. 1, the clutch members 37 and 38 are separated 100 and no motion is communicated from the rotating drive shaft S to the vertical operating shaft C on the wash tub. To bring about such engagement, the operator grasps the two handles 47, 48, and by depressing 105 the handle 47 and overcoming the force of the spring 46, withdraws the locking pawl member 44. By continuing the downward movement, the operator swings the lever 41 on its pivot 42, and thus brings the two 110 clutch members 37, 38, into operative engagement. That part of the plate or casting H carrying at its upper end the aperture 45 may, manifestly, be provided with a second aperture or notch 45, adapted to 115 receive the locking pawl 44 when the lever 41 is in its lowest position, whereby the operative engagement of the clutch members 37, 38, may be positively maintained as long as it is desired to operate the vertical shaft 120 C. Such second locking aperture 45 is not shown in the drawing but will be readily understood.

The wringer as a whole is indicated by the letter W, and is removably attached to 125 parts of the plate or casting H by a metallic bracket indicated as a whole by the letter V. Intermediate the wringer and the horizontal drive shaft S are suitable driving mechanisms, including means for reversing the 130

direction of rotation of the wringer rolls. This mechanism I will now proceed to describe.

At the outer end of the plate or housing 5 H, are three bracket arms 49, 50, and 51. The intermediate bracket arm 50 extends below, but in the plane of the drive shaft S and has an upwardly directed member 50* provided with a suitable aperture constituting a bearing 16 for the extreme end of the drive shaft S. The top bracket arm 49 is provided with a suitable and vertically arranged aperture therethrough, constituting a bearing for the lower member 53 of a reversing shaft, which member 53 normally projects somewhat above the upper surface 54 of said bearing bracket arm 49. This upper surface 54 constitutes a shoulder or support for the end 55 of the bracket arm 20 56 projecting from the bracket V herein-after described. The lower bracket arm 51 is provided with a supporting shoulder or surface indicated at 59, for another and lower extension 57 of the bracket V, and is 25 also provided with a pin or stud 58 which projects upwardly from the surface 59.

As shown, more particularly in Figs. 1, 3 and 5, the bracket V is provided with three lateral extensions 60, 56 and 57. The central extension 56 terminates in a circular boss 55 provided with a vertical aperture therethrough, adapted to fit over the upper end of the lower member 53 of the reversing shaft, as shown clearly in Figs. 3 and 5, with the lower horizontal surface of the boss 55 resting upon and being supported by the bearing surface 54 of the bracket arm 49. The bracket member 57 terminates in a boss 61 and is provided with a central, 40 vertical aperture therethrough, adapted to fit over the stud 58 on the bracket arm 51, with its lower surface resting upon and being supported by the surface 59 of said bracket arm 51.

Extending outwardly from the plate or casting H in the direction of the bracket arm 51, and depending downwardly from the lower side of the bracket arm 50 is a rib 62. This rib extends in a plane above the upper surface of the bracket arm 57 when the latter is in juxtaposition upon the bracket arm 51, as clearly shown in Fig. 5. The length of this rib 62 is such that its outer edge 63 projects over the outer margin of the lug 61 (see Fig. 7). In order, therefore, that the arm 57 may be positioned upon the stud 58 of the bracket arm 51, the bracket V must be swung in such position that a vertically arranged recess 64 in the margin of the boss 61 will register with the end 63 of the rib 62. When so registered, the wringer W and the frame V may be lifted in a vertical plane, until the boss 61 and the stud 58 are engaged or disengaged, 65 to position the bracket V upon the plate H

or to be moved bodily away from the same. In thus lifting the bracket V, so that the arm 57 will be disengaged from the stud 58, it is manifest that the boss 55 of the bracket 56 will be similarly lifted above 70 and disengaged from the upper end of the shaft member 53. This disengaged position is clearly shown in Fig. 3. Similarly, when the wringer W is to be attached to the machine, its angular position must be such as 75 to cause the end 63 of the rib 62 to register with the recess 64, whereupon by centering the aperture in the arm 57 over the stud 58, and the aperture in the boss 55 over the upper end of the shaft member 53, the 80 wringer mechanism as a whole may be moved bodily downward into proper operative engagement. When engaged as shown in Figs. 1, 2 and 5, it is manifest that the wringer mechanism as a unit may be swung 85 bodily in a horizontal plane, about the central longitudinal axis of the stud 58 and of the shaft member 53 as a pivotal center, into any desired position, as for example those indicated by full and by dotted lines 90 in Fig. 2.

To lock the wringer in any one of the desired positions, a horizontally arranged plate 65 is suitably secured at 90 to the upper bracket arm 49 of the plate H. Said 95 plate 65 is provided on its periphery with a plurality of locking notches 66. Mounted at 67 upon the bracket member V is a rock arm 68 having a locking bolt 69 and two handles 70, 70. A spring 71 interposed between the bracket member V and the rock arm 68 tends to press the bolt 69 downwardly and when the bolt 69 is engaged in the one of the notches 66 to hold said bolt in said notch and thus lock the wringer in 100 the desired position with respect to the plate 65. Two handles 70, 70, are provided for the convenience of the operator and are, manifestly, of great convenience, in operating from either side of the wringer W. 110

In the wringer frame W there is provided the usual horizontally disposed wringer rolls, the shaft X of one of which is so elongated as to project outwardly through a suitable bearing in the bracket V and to 115 carry on its outer end a suitable beveled gear Y. Upon the lower member of the shaft 53 is a beveled gear Z, the teeth z of which are adapted to mesh with the teeth of the beveled gear Y and thus transmit 120 motion through the gear Y to the wringer roller shaft X.

The bevel gear Z is a double gear, and on its under face it is provided with teeth 72. These teeth engage with the teeth of two 125 beveled gears Q, Q', loosely mounted upon the driving shaft S. Each beveled gear is provided on its inner face with clutch members 73, 74 respectively. Mounted upon the drive shaft S intermediate the bevel gears 130

Q, Q', is a sleeve R provided on its outer faces with clutch projections 75, 76 adapted to engage the clutch surfaces 73, 74, on the gears Q, Q', respectively, when the sleeve R is moved into engagement with one or the other of said gears. The sleeve R is adapted to slide longitudinally of the shaft S by means of the usual spline or feather arrangement 77. It will be understood that 10 the sleeve R rotates with the shaft S. It follows that when the sleeve R is moved into contact with the bevel gear Q, the clutch surfaces 73, 75 serve as a means of locking the gear Q to the shaft S, and thus 15 the movement of the shaft S is communicated through the gear Q to the gear Z and through the intermeshing gear Y to the shaft X. When the sleeve R is moved in the opposite direction so that the clutch faces 20 76, 74 interlock, the bevel gear Q' is similarly locked to the shaft S (while the gear Q turns loosely on said shaft) and thus the motion of the shaft S is communicated through the gear Q' to the gear Z and 25 through the gears Z and Y to the shaft X.

It will be further understood that when the bevel gear Q is thus locked to the shaft S, the gear Z will turn in one direction, while it will be turned in the opposite direction when the gear Q' is locked to the shaft S. The reversal of movement of the gear Z by means of the shifting of the sleeve R along the shaft S is effected by the following mechanism:

30 The sleeve R is provided with a peripheral annular groove 78 and a lug 79 loosely fits within said groove. Said lug 79 is mounted upon a yoke or circular arm 80 that projects downwardly from and is secured to the lower end of the shaft member 53. The lower end of the arm 80 is provided with a laterally disposed, horizontally arranged boss 81, which rests upon and is supported by the upper surface of the laterally extending bracket arm 50. A vertically arranged aperture 82 extends through the arm 50 in axial alignment with the shaft 53 and a stud 83 is secured to and projects downwardly from the boss 81, so that its lower end enters 35 the aperture 82. It will thus be understood that when the shaft 53 is rotated to the right or left in its bearings, around its longitudinal axis, the curved yoke arm 80 will move the lug 79 to the right or to the left; and 40 since said lug rests within the walls of the annular, circumferential groove 78 in the rotating sleeve R, it follows that said sleeve R will be forced to slide along the shaft S to the right or to the left as the occasion 45 may be.

The lower member of the shaft 53 is rotated on its longitudinal axis in the following manner: The handle 84 is pivotally mounted at 50 to the free end of the upper shaft member 86; said shaft member

being vertically mounted in a bearing 60^a in the outer end of the bracket arm 60, its lower end extending partway into the vertical aperture in the boss 55. This shaft member 50 will be conveniently held in the position 70 thus described by any suitable means, as for example, by pins 87. The lower end of the shaft member 86 is bifurcated or otherwise suitably shaped, as indicated at 88, to have interlocking engagement with the upper end 75 of the shaft member 53, so that motion of rotation applied to the shaft member 86 will be communicated to the shaft member 53. By pivotally connecting the handle member 84 to the upper end of the shaft member 86, 80 as clearly illustrated in Figs. 5 and 6, the handle 84 may be turned to one side or the other of the wringer frame W, as indicated in dotted lines in Fig. 6, so that the operator may readily actuate the handle, from which ever side of the machine he happens to be standing. The two shafts 86 and 53 together with the handle 84 and the yoke arm 80 and its connections, constitute the means for reversing the direction of the wringer roll 90 shaft X.

To protect the beveled gear reversing mechanism, I provide removable housing or cover plates 89, which at their lower ends fit nicely against the side margins of the bracket arm 50 and extend upwardly so as to fit around and cover also the beveled gear Z, the plates 89 being conveniently bolted together by bolts 90. Said housing plates are suitably apertured at 91, as shown in Fig. 9, so as to nicely and snugly fit around the flanges on the plate H leading up to and supporting the bracket arm 49. I find it convenient to make the plate 65 in two parts, as shown in Fig. 9, and to make one of the 100 parts and one portion of the covering plates 89 integral and to provide on the cover plate parts suitably apertured lugs 92 for the bolts 90.

A similar pair of housing or covering plates 93 are bolted together as indicated at 94 around the bevel gear and are suitably supported upon the flange 95 of the bracket V by the bolt 96.

It will be observed that while the wringer 110 frame W may be easily swung in a horizontal plane into any predetermined position desired, the frame is easily locked in the designated position; and also that the act of unlocking in order to swing the frame, may 120 be accomplished readily by reason of the fact that one of the handles 70 is provided on each side of the frame and is very accessible for the user to grasp.

It will also be noted that while the 125 wringer frame W is removable from the fixed support, the separation of the frame from the support is a very simple matter, requiring no bolts to be removed but merely the swinging of the frame into such a posi-

tion that the recess 64 will register with the rib 62. It will also be noted that the bodily vertical lifting of the wringer frame to disengage its supporting arms 56 and 57 from the bracket arms 49 and 51 will automatically separate the gears Y and Z; while these gears are automatically brought into mesh when the frame is positioned on the fixed support.

10 The handle for controlling the reversing unit, it will be noticed, is also accessible to the user from either side of the machine, being mounted on a horizontal pivot pin, so as to be readily swung, in a vertical plane, 15 from one side to the other by the user, and being swung in a horizontal plane to actuate the reversing unit.

The coverings for the gears make the device perfectly safe, protecting the user 20 having the sleeve or other parts of a garment from being caught in the moving parts, and yet these parts are readily accessible for oiling, repair or other purpose by simply removing the covers,—their construction being such that they may be quickly and easily 25 replaced by the user. The plate H and the bracket arms being integral, affords a structure light in weight with maximum of strength.

30 I claim as my invention:

1. A fixed support, a rotatable driving shaft horizontally mounted thereon, a frame pivotally mounted on the fixed support and adapted to swing in a horizontal plane, a 35 driven shaft horizontally mounted in said frame, means intermediate the shafts for communicating motion from the driving to the driven shaft, said means including mechanism for reversing the direction of motion 40 of the driven shaft, and a handle disassociated from the frame and adapted to swing both in a vertical and a horizontal path of movement for controlling the reversing mechanism.

45 2. A fixed support, a rotatable driving shaft horizontally mounted thereon, a frame pivotally mounted on the fixed support and adapted to swing in a horizontal plane, a driven shaft horizontally mounted in said 50 frame, means intermediate the shafts for communicating motion from the driving to the driven shaft, said means including mechanism for reversing the direction of motion of the driven shaft, and a handle disassociated from the frame and adapted to swing both in a vertical and a horizontal path of 55 movement for controlling the reversing means, said reversing and motion communicating means including a gear on the driven shaft, and a pair of loosely mounted gears on the driving shaft.

60 3. A fixed support, a horizontally disposed rotatable driving shaft mounted thereon, driving gears mounted on said support, a 65 frame pivotally and removably mounted on

said support and adapted to swing in a horizontal plane, a driven shaft on said frame, a gear on said driven shaft and adapted to automatically mesh with one of said driving gears when the frame and the fixed support 70 are brought into operative relationship, and to automatically separate from the driving gear when the frame is removed from the fixed support.

4. A fixed support provided with a rotatable driving shaft, a pair of bevel gears loosely mounted on said shaft, a clutch sleeve splined to said shaft intermediate said bevel gears and slidably longitudinally thereon, complemental clutch devices on the ends of 80 the clutch sleeve and the adjacent faces of said gears, means for operating said clutch sleeve, a frame removably mounted upon the fixed support, a driven shaft mounted horizontally in said frame with one end projecting from the margin thereof, a bevel gear on the projecting driven shaft end, and a bevel gear having a set of teeth on its opposite faces, one set meshing with the bevel 85 gears loosely mounted on the driving shaft 90 and the other set adapted to mesh with the teeth of the gear on the driven shaft.

5. A fixed support provided with a rotatable driving shaft, a pair of bevel gears loosely mounted on said shaft, a clutch sleeve 95 splined to said shaft intermediate said bevel gears and slidably longitudinally thereon, complemental clutch devices on the ends of the clutch sleeve and the adjacent faces of said gears, means for operating said clutch 100 sleeve, a frame removably mounted upon the fixed support, a driven shaft mounted horizontally in said frame with one end projecting from the margin thereof, a bevel gear on the projecting driven shaft end, and a 105 bevel gear having a set of teeth on its opposite faces, one set meshing with the bevel gears loosely mounted on the driving shaft and the other set adapted to mesh with the teeth of the gear on the driven shaft, said 110 clutch operating means comprising a yoke arm adapted to swing on a vertical axis, an operative connection between the yoke arm and the clutch sleeve and a handle for actuating the yoke arm.

6. A fixed support provided with a rotatable driving shaft, a pair of bevel gears loosely mounted on said shaft, a clutch sleeve splined to said shaft intermediate said bevel gears and slidably longitudinally thereon, complemental clutch devices on the ends of 115 the clutch sleeve and the adjacent faces of said gears, means for operating said clutch sleeve, a frame removably mounted upon the fixed support, a driven shaft mounted horizontally in said frame with one end projecting from the margin thereof, a bevel gear on the projecting driven shaft end, a 120 bevel gear having a set of teeth on its opposite faces, one set meshing with the bevel 125 gears.

65 7. A fixed support, a horizontally disposed rotatable driving shaft mounted thereon, driving gears mounted on said support, a frame pivotally and removably mounted on

- gears loosely mounted on the driving shaft and the other set adapted to mesh with the teeth of the gear on the driven shaft, said clutch operating means comprising a yoke 5 arm, a connection between said arm and the clutch sleeve, a pivotal bearing on the fixed support for said yoke arm whereby the latter may swing on a vertical axis, and means for actuating said yoke arm.
10. A fixed support, a metal plate secured thereon, three bearing brackets projecting laterally from one end of said plate and beyond the margin of the fixed support, the intermediate bracket having an upturned 15 member provided with a horizontally arranged shaft bearing aperture, a shaft bearing on the plate, the longitudinal axis of which is in alinement with that of said shaft bearing aperture, a rotatable driving shaft 20 in said plate bearings, a vertical shaft bearing in the upper bearing bracket of said plate, a pivotal stud on the lower bearing bracket, a frame pivotally mounted on the upper and lower bearing brackets, a driven 25 shaft in said frame and means for operating the driven shaft from the driving shaft.
8. A fixed support, a metal plate secured thereon, three bearing brackets projecting laterally from one end of said plate and 30 beyond the margin of the fixed support, the intermediate bracket having an upturned member provided with a horizontally arranged shaft bearing aperture, a shaft bearing on the plate, the longitudinal axis of 35 which is in alinement with that of said shaft bearing aperture, a rotatable driving shaft in said plate bearings, a vertical shaft bearing in the upper bearing bracket of said plate, a pivotal stud on the lower bearing 40 bracket, a frame pivotally mounted on the upper and lower bearing brackets, a driven shaft in said frame and means for operating the driven shaft from the driving shaft, said means including bevel gears on the driving 45 and driven shafts.
9. A fixed support, a metal plate secured thereon, three bearing brackets projecting laterally from one end of said plate and beyond the margin of the fixed support, the 50 intermediate bracket having an upturned member provided with a horizontally arranged shaft bearing aperture, a shaft bearing on the plate, the longitudinal axis of which is in alinement with that of said shaft bearing aperture, a rotatable driving shaft in said plate bearings, a vertical shaft bearing in the upper bearing bracket of said plate, a pivotal stud on the lower bearing bracket, a frame pivotally mounted on the 55 upper and lower bearing brackets, a driven shaft in said frame and means for operating the driven shaft from the driving shaft, said means comprising intermeshing gears on the driving and driven shafts and a gear 60 reversing mechanism.
10. A fixed support, a rotatable driving shaft mounted thereon, vertically arranged pivotal studs on said support, a wringer frame, bearings on said frame adapted for operative engagement with said pivotal 70 studs, a driven shaft on said frame, and means for operatively connecting the driving and the driven shafts.
11. A fixed support, a rotatable driving shaft mounted thereon, vertically arranged 75 pivotal studs on said support, a wringer frame, bearings on said frame adapted for operative engagement with said pivotal studs, a driven shaft on said frame, and means for operatively connecting the driving 80 and the driven shafts, said means embracing mechanism for reversing the direction of rotation of the driven shaft.
12. A fixed support, a rotatable driving shaft mounted horizontally thereon, a 85 bracket arm on said support above and another below said driving shaft, a bearing shoulder on the lower bracket, a stud projecting vertically upward from said shoulder, a bearing shoulder on the upper bracket 90 arm, a frame, a rotatable shaft therein, a bracket secured to one margin of the frame provided with a bearing arm adapted for engagement with the stud on said lower bracket arm, a second bearing arm adapted 95 for operative engagement with the bearing shoulder on the upper bracket arm embracing a pivotal connection in vertical alinement with said stud, and means for maintaining the lower bearing arm and the stud 100 supporting lower bracket arm in operative relation.
13. A fixed support, a rotatable driving shaft mounted horizontally thereon, a bracket arm on said support above and another below said driving shaft, a bearing shoulder on the lower bracket, a stud projecting vertically upward from said shoulder, a bearing shoulder on the upper bracket arm, a frame, a rotatable shaft therein, a 105 bracket secured to one margin of the frame provided with a bearing arm adapted for engagement with the stud on said lower bracket arm, a second bearing arm adapted 110 for operative engagement with the bearing shoulder on the upper bracket arm embracing a pivotal connection in vertical alinement with said stud, and means for maintaining the lower bearing arm and the stud supporting lower bracket arm in operative 115 relation, said means embracing an overhanging rib on the fixed support.
14. A fixed support, a rotatable driving shaft mounted horizontally thereon, a bracket arm on said support above and another below said driving shaft, a bearing shoulder on the lower bracket, a stud projecting vertically upward from said shoulder, a bearing shoulder on the upper bracket arm, a frame, a rotatable shaft therein, a 120 125 130

bracket secured to one margin of the frame provided with a bearing arm adapted for engagement with the stud on said lower bracket arm, a second bearing arm adapted 5 for operative engagement with the bearing shoulder on the upper bracket arm embracing a pivotal connection in vertical alinement with said stud, and means for maintaining the lower bearing arm and the stud 10 supporting lower bracket arm in operative relation, while permitting their separation when so desired.

15. A fixed support, a rotatable driving shaft mounted horizontally thereon, a bracket arm on said support above and another below said driving shaft, a bearing shoulder on the lower bracket, a stud projecting vertically upward from said shoulder, a bearing shoulder on the upper bracket 20 arm, a frame, a rotatable shaft therein, a bracket secured to one margin of the frame provided with a bearing arm adapted for engagement with the stud on said lower bracket arm, a second bearing arm adapted 25 for operative engagement with the bearing shoulder on the upper bracket arm embracing a pivotal connection in vertical alinement with said stud, and means for maintaining the lower bearing arm and the stud 30 supporting lower bracket arm in operative relation, said means embracing a vertically disposed recess in the margin of the lower bearing arm and a rib projecting from the fixed support with its lower edge overhanging 35 the said lower bearing arm to prevent any substantial vertical movement of the latter excepting only when said recess and said rib are in vertical alinement.

16. A fixed support, a rotatable driving shaft mounted thereon, vertically arranged pivotal studs on said support, a wringer frame, bearings on said frame adapted for operative engagement with said pivotal studs, a driven shaft on said frame, and 45 means for operatively connecting the driving and the driven shafts, said means embracing a gear unit on the driving shaft for reversing the direction of rotation of the driven shaft, and means on the frame connected with said reversing unit for operating the latter.

17. A fixed support, a rotatable driving shaft mounted thereon, vertically arranged pivotal studs on said support, a wringer frame, bearings on said frame adapted for operative engagement with said pivotal studs, a driven shaft on said frame, and means for operatively connecting the driving and the driven shafts, said means embracing a gear unit on the driving shaft 55 for reversing the direction of rotation of the driven shaft, and means on the frame connected with said reversing unit for operating the latter from either side of the frame.

65. 18. A fixed support, a rotatable driving

shaft mounted thereon, vertically arranged pivotal studs on said support, a wringer frame, bearings on said frame adapted for operative engagement with said pivotal studs, a driven shaft on said frame, and 70 means for operatively connecting the driving and the driven shafts, said means embracing a three gear unit, a clutch on the driving shaft intermediate two of said gears, an operating handle on the frame connected 75 with said clutch.

19. A fixed support, a rotatable driving shaft mounted horizontally thereon, a wringer frame removably mounted on pivotal studs upon said support and adapted to 80 swing in a horizontal plane, coöperative means upon the fixed support and said frame, adapted for locking the latter to the former in a desired position, a driven shaft on said frame and means for operatively 85 connecting the driving and driven shafts.

20. A fixed support, a rotatable driving shaft mounted horizontally thereon, a wringer frame removably mounted on pivotal studs upon said support and adapted 90 to swing in a horizontal plane, coöperative means upon the fixed support and said frame, adapted for locking the latter to the former in a desired position, a driven shaft on said frame, means for operatively 95 connecting the driving and driven shafts, said locking means comprising a horizontally disposed plate on the fixed support, a locking notch in said plate and a locking lug on the frame adapted to engage said 100 notch.

21. A fixed support, a rotatable driving shaft mounted horizontally thereon, a wringer frame removably mounted on pivotal studs upon said support and adapted 105 to swing in a horizontal plane, coöperative means upon the fixed support and said frame, adapted for locking the latter to the former in a desired position, a driven shaft on said frame, and means for operatively 110 connecting the driving and driven shafts, said means embracing mechanism for reversing the direction of rotation of the driven shaft.

22. A fixed support, a rotatable driving 115 shaft mounted horizontally thereon, a wringer frame removably mounted on pivotal studs upon said support and adapted to swing in a horizontal plane, coöperative means upon the fixed support and said 120 frame, adapted for locking the latter to the former in a desired position, a driven shaft on said frame and means for operatively connecting the driving and driven shafts, said locking means comprising a pivoted 125 locking bolt on the frame, a horizontally disposed plate on the fixed support, a notch in said plate and a handle for operating said locking bolt.

23. A fixed support, a rotatable driving 130

- shaft mounted horizontally thereon, a wringer frame removably mounted on pivotal studs upon said support and adapted to swing in a horizontal plane, coöperative means upon the fixed support and said frame, adapted for locking the latter to the former in a desired position, a driven shaft on said frame and means for operatively connecting the driving and driven shafts,
- 5 10 15 20 25 30 35 40 45 50 55 60 65 70 75 80 85 90
- 10 said locking means comprising a pivoted locking bolt on the frame, a horizontally disposed plate on the fixed support, a notch in said plate and two handles for operating said bolt, one on each side of the frame.
- 15 24. A fixed support, a plate on said support, a horizontally disposed shaft bearing in said plate, a driving shaft rotatably mounted in said bearing, a bracket extending from the plate end outwardly below and then upwardly toward the plane of the axis of the driving shaft, a bearing for the end of the driving shaft in said bracket, a bracket extending from the plate above the driving shaft, a vertically arranged bearing in said last mentioned bracket, a driven shaft rotatably mounted in said last mentioned bearing, and reversing gear mechanism on said shafts intermediate said bearings.
- 20 25. A fixed support, a plate on said support, a horizontally disposed shaft bearing in said plate, a driving shaft rotatably mounted in said bearing, a bracket extending from the plate end outwardly below and then upwardly toward the plane of the axis of the driving shaft, a bearing for the end of the driving shaft in said bracket, a bracket extending from the plate above the driving shaft, a vertically arranged bearing in said last mentioned bracket, a driven shaft rotatably mounted in said last mentioned bearing, reversing gear mechanism on said shafts intermediate said bearings, and housing plates surrounding said reversing gears and removably secured to said brackets.
- 25 30 35 40 45 50 55 60 65 70 75 80 85 90
26. A fixed support, a plate mounted thereon, a rotatable shaft horizontally mounted on said plate, gears on said shaft, a housing for said gears, a frame pivotally mounted on the plate and adapted to swing in a horizontal plane, a second plate integral with the housing and provided with notches in its margin, a bolt on the movable frame adapted for operative engagement with said notches to lock the frame in a desired position.
27. A fixed support, a plate on said support, a horizontally disposed shaft bearing on the plate, a bracket extending outwardly and upwardly from the plate end, a shaft bearing in the bracket in axial alinement with the first mentioned bearing, a rotatable driving shaft mounted in said bearings, reversing gears on the shaft intermediate said bearings, a housing for said gears, a frame pivotally mounted on the plate and adapted to swing in a horizontal plane, a bolt on said movable frame and locking notches on the gear housing adapted to be engaged by said bolt.
28. A fixed support, a plate on said support, a horizontally disposed shaft bearing on the plate, a bracket extending outwardly and upwardly from the plate end, a shaft bearing in the bracket in axial alinement with the first mentioned bearing, a rotatable driving shaft mounted in said bearings, reversing gears on the shaft intermediate said bearings, a housing for said gears, a frame pivotally mounted on the plate and adapted to swing in a horizontal plane, a bolt on said movable frame and locking notches on the gear housing adapted to be engaged by said bolt, said housing comprising a pair of covers removably bolted together and to said plate.

In testimony that I, GLENN MORE, claim the foregoing as my invention I affix my signature in the presence of two witnesses, this 12th day of March, A. D. 1919.

GLENN MORE.

Witnesses:

MAE LARSEN,
FLORENCE SUNDERLAND.
